ABSTRACT OF THE DISCLOSURE

Ethylbenzene contained in a C₈-aromatic stream is effectively isomerized to xylene isomers by carefully controlling the C₈-naphthalene content in said stream in an amount of about 2 wt. percent to about 9 wt. percent of the C₈-aromatics contained in said stream.

CROSS-REFERENCES TO RELATED APPLICATIONS

This application is a continuation-in-part of our pending application Ser. No. 692,655, filed Dec. 22, 1967, now abandoned.

BACKGROUND OF INVENTION

This invention relates to a C₈-alkylaromatic isomerization process. More particularly, this invention relates to an improved C₈-alkylaromatic process wherein ethylbenzene is effectively isomerized to xylenes without incurring excessive C₈-aromatic cracking and hydrogenation loss.

Processes for the production of the various xylene isomers have acquired significant interest and importance within the petroleum and petrochemical industries. Currently, this interest stems from the demand for para-xylene as an intermediate for the synthetic fiber and fabric industry.

Several currently available processes are effective for isomerizing only the xylene isomers and not the ethylbenzene C₈-aromatic isomer. Attempts to isomerize ethylbenzene to xylenes result in cracking losses which render the process economically unfeasible.

DESCRIPTION OF PRIOR ART

In the prior art, Holm, U.S. Pat. No. Re. 25,753 describes a method for isomerizing a non-equilibrium mixture of xylenes and ethylbenzene towards equilibrium. Essentially, the method rests upon the hypothesis that the co-existence of the corresponding naphthalenes is essential to the success of the method. Attention is directed toward a two-step process in which hydroisomerization and subsequent dehydrogenation are segregated, but data are also given for a one-step process in which from about 10 to 30 percent of the C₈ cyclers are naphthalenes. These data show varying degrees of approach to equilibrium para-xylene in total xylenes which depends upon the depth of simultaneous hydrogenation of the aromatic. It would appear from the data presented, especially run numbers

2

4-1232 and 4-1214 of the Holm patent, that although para-xylene/xylene concentrations of about 21% and 25% respectively were obtained, saturation of C₈-aromatics was 10 and 35% respectively. It is noted that equilibrium para-xylene/xylene concentration at these conditions is approximately 24%.

SUMMARY OF INVENTION

We have found, however, that a careful selection of processing conditions and catalyst will give substantially equilibrium para-xylene/xylene and ortho-xylene/xylene concentrations, while saturating only a very minor portion of the C₈-aromatics to naphthalenes, when attempting to isomerize ethylbenzene or an ethylbenzene-containing xylene stream. By "substantial equilibrium" we mean an approach to at least 90% of the para-xylene/xylenes in the reactor effluent. Ortho-xylene equilibrium is a little more difficult to achieve. Hence, if ortho-xylene is the desired product from an ortho deficient feed, the term "substantial equilibrium" in this case would mean at least 80% of the equilibrium value predicted for the ortho-xylene mixture. The generally accepted equilibrium values (based on API sources) are tabulated below for our range of interest.

	Temperature, °K.	600	700	800
	Temperature, °C.	327	427	527
10	Mole percent of isomer (including ethylbenzene):			
	Ethylbenzene	6	8	11
	Para-xylene	22	22	21
15	Meta-xylene	50	48	45
	Ortho-xylene	22	22	23
20	Mole percent of isomer (in xylenes only):			
	Para-xylene	24	24	23
25	Meta-xylene	54	52	51
	Ortho-xylene	22	24	26

35 Depending on the circumstances, we shall sometimes refer to the equilibrium system which includes ethylbenzene and at other times to the xylene system only. The equilibrium between the C₈-aromatics and the C₈-naphthalenes 40 in the presence of added hydrogen is readily adjusted by changing temperature, hydrogen ratio, or pressure. These conditions are so correlated that the naphthalene content can be raised by either lowering temperature and/or raising pressure. Likewise, by either raising temperature and/or lowering pressure, the naphthalene content may be lowered.

45 When isomerization only among the xylenes is desired, without conversion of ethylbenzene to xylenes, only a trivial amount of C₈-naphthalenes are required, but when ethylbenzene conversion to xylenes is desired, then the range of 2% to 9% C₈-naphthalenes based on C₈-aromatics 50 is essential for efficient operation. Thus, a feed stock rich in ethylbenzene, which is by far the most common feed available from catalytic or pyrolytic sources, can be utilized. The advantage of this in commercial operation 55 is that, instead of having, for example, 30% additional feed as naphthalenes, recycling through the isomerization system, a value of less than 10% naphthalenes is completely adequate and makes for a more efficient and economical process. The advantage of the process of our invention is 60 that we have obtained very high efficiencies in converting ethylbenzene to xylene isomers without incurring naphthalene formation of greater than 10%. This also will be shown in great detail in the accompanying examples.

Therefore in an embodiment, this invention relates to an isomerization process for the production of a specific xylene isomer which comprises contacting hydrogen and a C₈-aromatic charge stock containing ethylbenzene at a concentration greater than equilibrium with respect to the xylenes present and containing C₈-naphthalenes at isomerization conditions in a reaction zone, with a catalytic composite of alumina combined with about 0.01% to about 1.0% by weight of platinum component and about 0.1% to about 5.0% by weight of a halogen component, separating a specific xylene isomer from the resulting reaction product effluent and providing a hydrocarbon stream containing unreacted ethylbenzene, C₈-naphthalenes and xylene isomers, and recycling said hydrocarbon stream to said reaction zone; said process further characterized in that said isomerization conditions are selected to maintain a C₈-naphthalene content in said C₈-aromatic charge to said reaction zone of from 2.0% to about 9.0% by weight of the C₈-aromatics in said charge.

In further more limited embodiments said isomerization conditions include an LHSV of about 0.2 to about 8.0, a temperature of about 370° C. to about 450° C., a pressure of about 3 atmospheres to about 20 atmospheres, and a hydrogen concentration in a mole ratio of about 2.0:1 to about 20.0:1 with respect to said C₈-aromatic charge. In addition, 1.0 to about 1000 p.p.m. by weight halogen may be added to said C₈-aromatic charge.

More specific embodiments and conditions will be found in the following more detailed description of this invention. As used herein, C₈-aromatic charge stock refers to the charge stock fed to the isomerization reaction zone. As is known to those trained in the art, the fresh feed, before being fed to the reactor may be first separated to recover a specific xylene isomer before it is passed to the reactor or the fresh feed may be combined with a recycle stream and fed directly to the reactor.

DESCRIPTION OF PREFERRED EMBODIMENTS

The process of our invention is applicable to certain hydrocarbon fractions containing ethylbenzene in an amount above its equilibrium value where an object of the invention is to produce one or more of the xylene isomers therefrom. The charging stock may be ethylbenzene alone or ethylbenzene in admixture with ortho-, meta-, or paraxylene, or a non-equilibrium mixture of the aforesaid C₈-aromatic hydrocarbons in which the ratio of isomers is other than the equilibrium portion of C₈-aromatic components, said mixture being either exclusively C₈-aromatic components or accompanied by other classes of hydrocarbons such as paraffins, other aromatic hydrocarbons, olefins, naphthalenes, etc., or a mixture of hydrocarbons including at least one of the aforesaid xylene isomers with other compounds inert in the present process. One of the preferred sources of the present charging stock is a fraction derived from certain petroleum conversion products containing aromatic hydrocarbons and including fractions boiling within the range of from about 120 to about 145° C. Suitable fractions utilizable in the process may be separated from gasoline produced by subjecting an appropriately boiling petroleum fraction to dehydrogenation as for example, a hydroformed gasoline boiling range fraction containing naphthalenic hydrocarbons. Such gasoline boiling range fractions may be produced either thermally and/or produced in a catalyzed cracking, reforming, or hydroforming reaction in accordance with procedures well known to the art.

The isomerization takes place in an isomerization zone maintained at a liquid hourly space velocity within the range of 0.2 to 8, and preferably within the range of 0.6 to 3, a temperature within the range of 370° C. to 450° C. and preferably within the range of 380° C. to 440° C., and a pressure within the range of 3 to 20 atmospheres and preferably within the range of 5 to 18 atmos-

pheres in the presence of not less than 2.0 nor more than 9 weight percent C₈-naphthalenes, and preferably in the range of 3 to 8 weight percent. A molal excess of hydrogen shall be furnished to the isomerization zone, usually in the range of about 2.0 to 20 moles of hydrogen per mole of hydrocarbon feed.

The catalyst utilized in the present process comprises alumina, a platinum component, and combined halogen with said catalyst being disposed within the reaction zone. The alumina support may be a high surface area alumina such as gamma-, eta-, and theta-alumina, although these are not necessarily of equivalent suitability. By the term "high surface area" is meant a surface area measured by surface area techniques within a range of from 25 to 500 or more square meters per gram, and preferably a surface area of approximately 100 to 300 square meters per gram.

The platinum component of this catalyst for use in our invention will normally be utilized in an amount of from about 0.01 to about 1.0% by weight based upon the solid support. Of the various halogens which may be utilized, both fluorine and chlorine can be used satisfactorily either separately or together. Normally, the halogen content of the catalyst ranges from 0.1% to 5% by weight, and preferably from 1% to 4%, also, it is contemplated within the scope of this invention that halogen in an amount of from 0.0001 to 0.1% by weight of feed, and preferably in an amount of from about 0.001 to about 0.05% by weight of feed may be continuously added to the isomerization zone. We have unexpectedly found, when using this platinum-alumina-combined fluorine catalyst, that chlorine, in the range of from 0.001 to 0.05% by weight of feed is of feed may be continuously added to the isomerization of our invention. This halogen can be added by any suitable halogen-containing compound such as t-butylchloride.

As will be recognized by one skilled in the art, the process of this invention utilizing the catalyst hereinbefore set forth may be effected in any suitable manner and may comprise either a batch or continuous operation. The preferred method by which the process of this invention may be effected is the continuous type operation. Thus, a particularly preferred method of the fixed bed operation is one in which a non-equilibrium C₈-aromatic hydrocarbon fraction is continuously charged to the reaction containing the fixed bed of the desired catalyst, said zone being maintained at the proper operating conditions of temperature and pressure as described above. The reaction zone may comprise an unpacked vessel or coil or may be lined with an adsorbent packing material. The charge may be passed through the catalyst bed in an upward, downward, or radial flow and the isomerized product may be continuously withdrawn, separated from the reactor effluent and recovered, while any unreacted starting materials may be recycled to form a portion of the feed stock to the reaction zone. It is within the scope of this invention to recover one or more specific xylene isomers as a product; for example, the process may be designed to produce para-xylene and/or ortho-xylene.

EXAMPLES

The following examples are introduced for the purpose of illustration only with no intention of unduly limiting the generally broad scope of the present invention.

Example I

A catalyst comprising 0.375 weight percent platinum, 3.5 weight percent fluoride, 0.1 weight percent chloride on a gamma-alumina support was placed in an isomerization zone. A charge stock comprising 100% o-xylene was charged to the isomerization zone at a liquid hourly space velocity of 5.0, a hydrogen to hydrocarbon mole ratio of 10:1, a pressure of 20.4 atmospheres and a temperature of 482° C. Charge stock and product analyses are shown in Table I below.

TABLE I

	Charge stock	Product
Ethylbenzene	1.2	
p-Xylene	10.2	
m-Xylene	38.9	
o-Xylene	100.0	46.4
C ₈ -naphthalenes		0.6
Other nonaromatics and benzene		1.4
Toluene		1.0
C ₉ +		0.3
Total, wt. percent	100.0	100.0
C ₈ ring retention		97.3

As can be seen from Table I, at low naphthalene concentrations, a very selective reaction occurs with substantially equilibrium conversion of para-xylene being obtained. The ethylbenzene which is produced is far less than equilibrium amounts. In general, the rate of reaction

5
tive to meta and each other. Ethylbenzene is not converted since the amount in the charge is below the equilibrium value. As used herein, C₈ ring retention is the percent of the original C₈-aromatics remaining as C₈-aromatics or converted to naphthalenes within the reactor.

Example III

A catalyst comprising 0.375 weight percent platinum, 2.3 weight percent chloride on a gamma-alumina support was placed in the isomerization zone. A charge stock containing 23.6 weight percent ethylbenzene was charged to the isomerization zone at varying space velocities, a hydrogen to hydrocarbon mole ratio of 5:1, a pressure of 10.2 atmospheres, and a temperature of 10 400° C. to 402° C.

15 The liquid hourly space velocities, as mentioned above were varied for each of the tests to vary conversions as shown below.

TABLE III

	Charge stock	Test 1	Test 2	Test 3
Ethylbenzene	23.6	14.0	9.9	16.8
p-Xylene	19.6	18.3	19.6	17.5
m-Xylene	56.1	42.2	41.5	43.6
o-Xylene	9.1	16.2	17.6	14.9
C ₈ -naphthalenes	0	6.1	6.5	5.1
Other nonaromatics and benzenes	0.5	2.0	2.9	1.3
Toluene	0.1	0.4	0.8	0.3
C ₉ +		0.8	1.2	0.5
Total, wt. percent	100.0	100.0	100.0	100.0
Total C ₈ -naphthalenes, wt. percent of charge		6.1	6.5	5.1
Liquid hourly space velocity		2	1	3
Total xylenes, wt. percent of charge		76.7	78.5	76.0
Percent para/total xylenes		23.9	24.9	23.0
Percent ortho/total xylenes		21.1	22.4	19.6
C ₈ ring retention		96.9	95.2	98.0

involving ethylbenzene toward equilibrium is slower than the rate of xylene isomerization. This shows that the presence of naphthalenes in a substantial concentration, as in the range of 2 to 9 weight percent is not necessary to isomerize a pure xylene feedstock.

Example II

A catalyst comprising 0.375 weight percent platinum, 1.73 weight percent fluoride, 0.39 weight percent chloride on a gamma-alumina support was placed in an isomerization zone. A charge stock containing a minor amount of ethylbenzene, namely 5.2 weight percent was charged to the isomerization zone at a liquid hourly space velocity of 2.0, a hydrogen to hydrocarbon mole ratio of 6:1, a pressure of 12.1 atmospheres and a temperature of 398° C. Chloride addition to the feed was maintained at 0.0025 weight percent of the feed by utilizing t-butylchloride. Charge stock and product analyses are shown in Table II below.

TABLE II

	Charge stock	Product
Ethylbenzene	5.2	5.2
p-Xylene	11.5	19.1
m-Xylene	71.3	48.4
o-Xylene	11.9	16.5
C ₈ -naphthalenes	6	8.6
Other nonaromatics and benzene	0.1	1.4
Toluene		0.3
C ₉ +		0.5
Total, wt. percent	100.0	100.0
Percent para/total xylenes		22.8
Percent ortho/total xylenes		19.6
C ₈ ring retention (percent)		97.8

As can be seen from the product analyses, ethylbenzene concentration remained the same but the ortho- and para-xylene have come to "substantial equilibrium" rela-

40 For all the tests shown, the para- and ortho-xylene are in "substantial equilibrium" with the meta-xylene.

Example IV

A catalyst comprising 0.375 weight percent platinum, 1.7 weight percent fluoride on a gamma-alumina support was placed in the isomerization zone. A charge stock containing a high ethylbenzene concentration, namely 43.0 weight percent was charged to the isomerization zone at a liquid hourly space velocity of 2.0, a hydrogen to hydrocarbon mole ratio of 6:1, a pressure of 11.9 atmospheres and at a temperature of 405° C. Chloride addition to the feed was maintained at 0.0025 weight percent (of the feed). Charge stock and product analyses are shown in Table IV below.

TABLE IV

	Charge stock	Product
Ethylbenzene	43.0	23.5
p-Xylene	8.1	15.6
m-Xylene	41.3	36.0
o-Xylene	7.1	13.3
C ₈ -naphthalenes	0	8.3
Other nonaromatics and benzene	0.4	2.4
Toluene	0.1	0.3
C ₉ +		9.6
Total, wt. percent	100.0	100.0
Percent para/total xylenes		24.1
Percent ortho/total xylenes		20.5
Total xylenes, weight percent of feed	56.5	64.9
C ₈ ring retention		96.8

70 The operation resulted in an appreciable conversion of the ethylbenzene to mixed xylenes which, in a recycle operation, would be more efficient yet because the C₈-naphthalenes have already been produced in essentially equilibrium concentration and would not subtract further from the C₈-aromatics in the feed. Substantially equilibrium concentration of para- and ortho-xylene was observed.

7
Example V

The same catalyst utilized for the preceding example was utilized for a charge stock containing a slightly higher concentration of ethylbenzene, namely 46.0 weight percent. This charge stock was charged to the isomerization zone at a liquid hourly space velocity of 2.0, a hydrogen to hydrocarbon mole ratio of 6:1, a pressure of 12.1 atmospheres, and a temperature of 403° C. Chloride addition to the feed was maintained at 0.0025 weight percent (of the feed). The total weight percent C₈-naphthalenes in the effluent was 6.1 weight percent. Charge stock and product analyses are shown in Table V below.

TABLE V

	Charge stock	Product
Ethylbenzene	46.0	31.0
p-Xylene	8.1	14.5
m-Xylene	38.7	33.8
o-Xylene	6.7	12.2
C ₈ -naphthalenes	0	6.1
Other nonaromatics and benzene	0.2	1.5
Toluene	0.1	0.3
C ₉ +	0.2	0.6
Total, wt. percent	100.0	100.0
Percent para/total xylenes	24.0	
Percent ortho/total xylenes	20.1	
Weight percent total xylenes		
Based on charge	53.5	60.5
C ₈ ring retention		98.1

Again, the conversion of the ethylbenzene to mixed xylenes is efficient considering also the C₈-naphthalenes found, and the para- and ortho-xylene are in substantial equilibrium with the meta-xylene.

Example VI

A catalyst comprising 0.375 weight percent platinum, 1.7% chloride and 0.5% fluoride on a gamma-alumina support was placed in the isomerization zone. The charge stock containing 100.0 weight percent ethylbenzene was charged to the isomerization zone at a liquid hourly space velocity of 1.0, a hydrogen to hydrocarbon mole ratio of 5:1, a pressure of 6.8 atmospheres and at a temperature of 401° C. Chloride addition to the feed was maintained at 0.02 weight percent (of the feed). Charge stock and product analyses are shown in Table VI below.

TABLE VI

	Charge stock	Product
Ethylbenzene	100.0	67.9
p-Xylene		6.1
m-Xylene		12.9
o-Xylene		5.7
C ₈ -naphthalenes		3.4
Other nonaromatics and benzene		2.4
Toluene		0.9
C ₉ +		0.7
Total, wt. percent	100.0	100.0
Percent para/total xylenes	24.7	
Percent ortho/total xylenes	23.1	
Weight percent xylenes as feed	24.7	
C ₈ ring retention		96.0

8

As can be seen from the product analysis, it is apparent that the present catalyst and conditions of operation are greatly superior in accomplishing isomerization of any C₈-aromatic, including ethylbenzene, in spite of the low naphthalene content of the system. It should also be noted that high yields of xylenes having substantially equilibrium concentration of para- and ortho-xylene were obtained.

Example VII

The feed stock of Example VII was processed over the same catalyst at the same conditions as Example VI except that the temperature was about 405° C. and the chloride addition to the feed was held at 0.04% by weight. Charge and product are shown below.

TABLE VII

	Charge stock	Product
Ethylbenzene	100.0	75.4
p-Xylene		3.2
m-Xylene		9.6
o-Xylene		4.5
C ₈ -naphthalenes		1.4
Other nonaromatics and benzene		4.9
Toluene		0.4
C ₉ +		0.6
Total, wt. percent	100.0	100.0
C ₈ ring retention, percent		94.1

30

It will be noted that a greater ring loss and lesser conversion resulted than in Example VI, attributable to an insufficient concentration of C₈-naphthalenes in the system. This results even though the change in processing conditions appears to be relatively insignificant.

As noted in these examples, isomerization of a particular xylene (Example I) to the other xylenes is accomplished readily without necessitating the presence of significant amounts of C₈-naphthalenes. On the other hand, when ethylbenzene is to be converted to xylenes in an efficient manner, concurrent with establishing the essential isomerization equilibrium among the xylenes, some C₈-naphthalenes are required.

In a typical recycle operation in which an average C₈-aromatic fraction including ethylbenzene is to be converted entirely to specific xylene isomers, the combined feed rate through the isomerization zone is several times larger than the fresh feed. Consider, for example, the conversion of the following feed to para-and/or ortho-xylene.

Fresh feed composition, wt. percent:

Ethylbenzene	24.0
Para-xylene	20.5
Meta-xylene	40.5
Ortho-xylene	15.0

When 100 weight units of this feed is supplied to a reaction/separation circuit which includes a crystallizer for para-xylene removal and a fractionator for ortho-xylene removal, and these removal devices are then operated to recover a predetermined fraction of the specific isomers desired, the following yields are obtainable.

Case	1	2	3	4	5
Percent recovery of para in crystallizer feed	62.4	60.9	61.2	61.4	38.1
Percent recovery of ortho in xylene fractionator feed	0	30	60	95	95
Combined feed ratio, based on unit weight of fresh feed	6.8	5.0	3.9	3.1	3.7
Yields, wt. percent:					5.6
Para-xylene	82.6	61.8	49.9	41.2	30.1
Ortho-xylene	0	25.4	40.1	50.8	60.2
C ₈ -naphthalenes in reactor, feed based on C ₈ -aromatics, wt. percent	4.7	5.5	5.9	6.1	5.9
C ₈ ring retention per pass	97	97	97	97	97
Reactor outlet conditions:					
Pressure, atm. gauge	10.2	10.2	10.2	10.2	10.2
Temperature, °C	409	407	406	405	408

It will be noted that the combined feed ratio to the isomerization zone varies from about 3.1 to about 6.8 times the fresh feed. The C₈-naphthalene concentration required in the reaction zone varies somewhat because the extent of conversion required per pass for the ethylbenzene depends upon the combined feed ratio. In all cases the C₈-naphthalene level is chosen to result in a C₈ ring retention of 97%. Small changes in pressure and/or temperature accomplish this control because the C₈-naphthalenes are in essential equilibrium with the C₈-aromatics at the reactor outlet. These naphthalenes are automatically returned to the reactor with the unconverted ethylbenzene and xylenes to prevent the formation of additional amounts of naphthalenes from the fresh feed. It is to be realized that some naphthalenes must be formed in the reactor to offset losses incurred elsewhere in the total system. It has thus been shown that the presence of about 2 to about 9 weight percent naphthalenes is critical to the effective isomerization of ethylbenzene in both a recycle process and a once-through operation.

We claim as our invention:

1. An isomerization process for the production of a specific xylene isomer which comprises contacting hydrogen and a C₈-aromatic charge stock containing ethylbenzene at a concentration greater than equilibrium with respect to the xylenes present and containing C₈-naphthalenes at isomerization conditions in a reaction zone, with a catalytic composite of alumina combined with about 0.01% to about 1.0%, by weight, of a platinum component and about 0.1% to about 5.0%, by weight, of a halogen component, separating a specific xylene isomer

from the resulting reaction product effluent and providing a hydrocarbon stream containing unreacted ethylbenzene, C₈-naphthalenes, and xylene isomers, and recycling said hydrocarbon stream to said reaction zone; said process further characterized in that said isomerization conditions are selected to maintain a C₈-naphthalene content in said C₈-aromatic charge to said reaction zone of from 2.0% to about 9.0% by weight, of the C₈-aromatics in said charge, said isomerization conditions including an LHSV of about 0.2 to about 8.0, a temperature of about 370° C. to about 450° C., a pressure of about 3 atmospheres to about 20 atmospheres, and a hydrogen concentration in a mole ratio of about 2.0:1 to about 20.0:1 with respect to said C₈-aromatic charge.

5 2. The process of claim 1 further characterized in that said specific xylene isomer is para-xylene.

3. The process of claim 1 further characterized in that said specific xylene isomer is ortho-xylene.

4. The process of claim 1 further characterized in that 10 from about 1.0 to about 1000 p.p.m., by weight, of halogen is added to said C₈-aromatic charge.
